UNITED STATES PATENT OFFICE.

JOSEPH M. THORPE, OF SAN FRANCISCO, CALIFORNIA.

FURRING NAIL.

Application filed May 19, 1927. Serial No. 192,504.

The invention relates to improvements in lath spacers or furring nail, particularly for use in spacing metal lath or wire netting a suitable distance away from a wall or surface to which a coating of some plaster composition is to be applied.

One object of the invention is the provision of a furring nail in which the spacing element is so formed that the paper usually put upon the wall, especially in stucco construction to prevent entrance of exterior moisture, will not be injured, and that the metal lath will be securely held and locked into a groove formed in the cap portion of the spacer.

Another object of the invention is to provide the body portion of a spacing element with a flanged opening having a mouth adapted to be in a firm engagement with a nail in all possible angular positions of the nail relative to the body portion, thus making it immaterial whether the nail is driven through the opening so as to be in a preferred right-angular position relative to the body portion or whether the nail is driven obliquely through the body portion, and thereby also making the nail applicable to the spacing element, and the latter applicable to a wall sheathing even by unskilled hands.

A further object is the provision of a lath spacer in which the spacer may be easily slid into position under the lath without raising the lath by hand. The spacer will conform to the angle at which the nail is driven and this angle may be so determined that in driving the nail the spacer will adjust itself, thus tensioning and spacing the wire at the same time.

With the foregoing and other objects in view, which will appear in the description, my invention resides in the construction and arrangement of parts hereinafter described and more particularly claimed, although I wish it to be understood that changes and details of construction may be made within the scope of the appended claims and without departing from the spirit of the invention.

Preferred embodiments of the invention are shown in the accompanying drawings, in which—

Figure 1 is a perspective view of one embodiment of the improved lath spacer, provided with a groove across the cap portion thereof and with legs extending from the

cap and having curved flanges thereon for seating the spacer upon a wall sheathing;

Figure 2 is a perspective view of a lath spacer, which is identical with the spacer shown in Figure 1, except that the spacer is cut off along the edge of the groove and at right angles to the longitudinal edge of the cap portion in order to provide a cheaper and smaller form adapted for use in restricted places;

Figure 3 is a top plan of a spacer of the type shown in Figure 1, the view showing the spacer as holding a section of a wire netting or lath secured upon a wall;

Figure 4 is a side elevation of another embodiment of a lath spacer, secured to a wall, a portion of which is shown in section, the view illustrating a nail as holding the twined wires of a wire netting securely within the transverse groove in the cap portion of the spacer;

Figure 5 is an end view of one of the lath spacers of the type shown in Figure 4, the view showing a nail driven transversely and obliquely into the spacer and how the flanges at the nail opening cling to the nail and firmly hold it in engagement with the spacer;

Figure 6 is a side elevation of a lath spacer, which is identical with the spacer shown in Figures 4 and 5, except that the spacer is cut off virtually squarely between the groove and the raised cap portion at one end of the spacer for the same purpose as the spacer shown in Figure 2;

Figure 7 is a longitudinal, mid-sectional elevation of a lath spacer of the type shown in Figure 4, the view showing in full lines the tapering flanges at the nail opening and indicating by dotted lines a nail driven obliquely in the longitudinal direction into the spacer and how the nail is firmly held by the flanges in engagement with the spacer;

Figure 8 is a sectional elevation, similar to Figure 7, but showing in full lines the flanges at the nail opening as being spread out and in a firm engagement with a nail, which is indicated by dotted lines as being driven substantially at right angles to the seating flanges into the spacer; and

Figure 9 is an enlarged top plan of the nail-engaging portion of the various forms of lath spacers, the view showing the shape of the flanges at the nail opening of a spacer.

In the drawings, the reference numeral 1 indicates the usual nail by which a lath

spacer is fastened to a wall. The reference numerals 2, 3, 4 and 5 indicate the body of the various modifications of the spacer which are contemplated. All of the different modifications of spacers are constructed of sheet metal and are formed with a substantially rectangular cap or body portion 6, which has therein a transverse groove 7, and in each body portion and virtually centrally of the groove is an opening 8, preferably formed by a flange 9, which extends inward from the body portion and at its junction therewith is of a round formation and of a circumference adapted to accommodate the shank of a respective nail 1 therein. Preferably at three virtually equidistant points 10 of this rounded portion the inward extension of the flange is substantially at right angles to the body portion, while at intermediate points the flange tapers so that the mouth of the opening 8 is virtually of a triangular shape, the sides of the triangle being indicated by the numeral 11 in Figure 9. By this construction the spacers are adapted to accommodate nails of different diameters, so that, even if a nail fits only loosely within the round flange portion of a spacer, the sides 11 of the flange will press on the nail driven into the spacer and firmly hold the nail in engagement therewith in various angular positions of the nail to the body portion, as shown in Figures 5, 7, and 8.

In Figures 1, 4, 5, 6, 7 and 8, the body portion 6 is shown as having at each end and on its outer side a projection 12 formed in any suitable manner. These end projections are adapted to be hooked between a wall 13 and a portion 14 of a wire netting, as shown in Figures 3 and 4, before the respective spacer is placed in position for the fastening of the wire netting thereto, and they serve as means for preventing the wire from sliding off the body portion before the wire is guided into the groove 7 and against the shank of the nail 1. Legs 15, each preferably provided with stiffening flanges 16 at its side edges, extend at virtually right angles from the body portion, which in the forms shown in Figures 1, 2 and 3 is somewhat longer than in the forms shown in Figures 4, 7 and 8, the projections 12 in the latter figures being spaced only sufficiently far from each other for receiving the head of a nail 1 between them.

In Figures 1, 2 and 3 each of the legs 15 is shown as having at its end edge a somewhat arcuate seating flange 17, the ends of which are curved toward the body portion 6, as shown at 18, and this flange is preferably shorter than the body portion. A spacer thus constructed is easily placed in position upon a wall without being liable to injure the insulation paper 19, with which the wall is usually covered, as shown in

Figure 4. By this construction a tensioning means for the wire netting upon the spacer is also provided, and the spacer is allowed to adjust itself to any angle at which the nail may be driven.

In the spacers 4 shown in Figures 4, 5, 7 and 8, as well as in the spacer 5 shown in Figure 6, each leg 15 has at its end edge a seating flange 20, both of the flanges 20 on each spacer being virtually in the same plane and at substantially right angles to the legs, and the flanges being of virtually the same length as the body portion 6. Because of their short body portions 6, the spacers 4 and 5 may be easily tilted endwise for spacing a wire netting from a wall, but it is obvious that they may also be tilted sidewise for the same purpose. In this connection it should be observed that, when the spacers are tilted endwise, the width of the flanges 20 is sufficient for preventing the flanges from digging into the paper on the wall. Furthermore, the insulation paper is of an oily nature so that the flanges easily slip over the paper, whether the spacers are tilted endwise or sidewise, without cutting or tearing the paper and thus allow the spacers to be readily placed in their wire-engaging positions on the wall.

The spacer 3 shown in Figure 2 is similar to the spacer 2 shown in Figures 1 and 3, except that the spacer 3 is cut off at one end adjacent to the groove 7 and substantially at right angles to the body portion, so that the spacer has only one projection 12 and that each of the legs 15 has a stiffening flange 16 only at one side edge, and the spacer 5 shown in Figure 6 is similar to the spacer 4, except that the spacer 5 is cut off virtually squarely at one end adjacent to the groove 7, so that, like the spacer 3, the spacer 5 has only one projection 12 on its body portion and only one flange 16 on each leg 15. On account of their reduced length the spacers 3 and 5 are particularly adapted to be secured near wall corners or in other places where there is insufficient room for fastening either of the spacers 2 and 4.

It is evident that the lath spacers described in the foregoing are simple in construction and efficient in application and that the desired spacing and tensioning of a lath may be accomplished quickly and easily by means thereof.

It is also evident that the projections 12 on each spacer, besides serving as means for guiding the wires 14 into the groove 7, aid in distributing the force of the hammer blows, when the nail 1 is being driven home through the spacer and into a wall 13. In addition, it should be observed that, when the wires are thus held by the nail head in engagement with the sides of the groove, the sharp-edged ribs 21, which are usually

formed on the inner side of the nail heads, can not cut into the wires so deeply as to cause their severance, which could result if the body portions 6 of the spacers were 5 not grooved transversely.

I claim as my invention:

1. In combination, a spacing element for a wire lath, comprising a sheet of metal bent intermediate its ends in the form of an arch, having an apex and limbs disposed in a spaced relation to each other, each of said side limbs terminating in an arcuate flange; means on the external surface of the arch to engage the wire and force the latter toward the center of the spacing element; and means extending through the arch for attaching the spacing element in position against a supporting surface.

2. A wire fastener comprising a spacing element of sheet metal bent intermediate its ends in the form of an arch, having an apex and side limbs disposed in a spaced relation to each other, each of said side limbs terminating in an arcuate flange; projections at each end of said apex at right angles to said side limbs for engaging and stretching the wire, the said apex having a wire-engaging groove formed at the central portion thereof and extending at right angles to said side limbs; and a cooperating nail projecting through the groove at the central point thereof when said nail is driven into a support against which said spacing element is seated.

3. A wire fastener comprising a spacing element of sheet metal bent intermediate its ends in the form of an arch, having an apex and side limbs disposed in a spaced relation to each other, each of said side limbs terminating in an arcuate flange; a wire-engaging projection formed on said apex for engaging and stretching the wire, a wire-engaging groove formed in said apex and extending at right angles to said side limbs; and a cooperating nail projecting through the groove at the central point thereof when said nail is driven into a support against which said spacing element is seated.

4. A wire fastener comprising a spacing element formed from a strip of sheet metal bent into an arch having an apex and spaced side limbs having their free ends cut into arcuate shape and flanged outwardly in opposite directions to form a pair of surface-engaging lips; and a cooperating nail projecting through said apex between said side limbs and adapted to be driven into a supporting surface and to retain the fastener in position.

5. A wire fastener comprising a spacing element of sheet metal bent intermediate its end so as to form a body portion and legs extending therefrom in a spaced relation to each other, each of the legs terminating in a seating flange, and the body portion having a transverse wire-engaging groove therein; a cooperating nail adapted to be driven through the body portion and through the groove for holding the wire in the groove when the nail is driven into a support and when the spacing element is seated on the support; and means connected with the body portion for holding the nail in a firm engagement with the spacing element in all possible angular positions of the nail relative to the body portion.

6. A wire fastener comprising a spacing element of sheet metal bent intermediate its ends so as to form a body portion and legs extending therefrom in a spaced relation to each other, each of the legs terminating in a seating flange, and the body portion having a transverse wire-engaging groove therein and a flanged opening in the groove; and a cooperating nail adapted to be driven through the flanged opening for holding the wire in the groove when the nail is driven into a support and when the spacing element is seated on the support, the flange of the opening being so tapered as to hold the nail in a firm engagement with the spacing element in all possible angular positions of the nail relative to the body portion.

7. A wire fastener comprising a spacing element of sheet metal bent intermediate its ends so as to form a body portion and legs extending therefrom in a spaced relation to each other, each of the legs terminating in a seating flange, and the body portion having a transverse wire-engaging groove therein; terminal projecting means on the outer side of the body portion for engaging and stretching the wire; a cooperating nail adapted to be driven through the body portion and through the groove for holding the wire in the groove when the nail is driven into a support and when the spacing element is seated on the support; and means connected with the body portion for holding the nail in a firm engagement with the spacing element in all possible angular positions of the nail relative to the body portion.

In testimony whereof I affix my signature.

JOSEPH M. THORPE.
